UNITED STATES PATENT OFFICE.

FRANZ MOSTERTS, OF BERLIN, GERMANY.

COMB.

SPECIFICATION forming part of Letters Patent No. 715,837, dated December 16, 1902.

Application filed September 4, 1900. Renewed August 9, 1902. Serial No. 119,034. (No model.)

To all whom it may concern:

Be it known that I, FRANZ MOSTERTS, merchant, a subject of the Emperor of Germany, residing at Berlin, Germany, have invented a 5 certain new and useful Improvement in Apparatus for Moistening the Scalp, of which the following is a specification.

This invention has for its object to provide convenient means for moistening the scalp 10 with medicinal and other liquids without unnecessarily affecting the hair.

In the accompanying drawings, Figure 1 is a vertical section, Fig. 2 a side view, and Fig. 3 an end view, of the scalp-moistener embodying my invention.

The device chiefly comprises a tube or hollow plate S, made of hard rubber or other suitable material and provided in front with a comb-shaped enlargement, the teeth of 20 which may be straight or curved and are hollow, so as form thin tubes to conduct liquid to the scalp. As shown, the connection between the comb-shaped member or enlargement and the tube S is by means of screw- 25 threads, so that the device can be readily taken apart for cleansing purposes and as readily assembled. Furthermore, the tube S, extending into the bulb or ball, prevents the latter from collapsing or being entirely com- 30 pressed, prevents the compressing of the bulb or ball, excepting on the sides, and at the same time serves to form a steady or directing part or handle by means of which the movement of the comb-shaped member can 35 be readily controlled, enabling the application of pressure longitudinally of the tube, and yet having a substantially yielding portion in contact with the hand of the operator. The rear part of the tube S extends into a 40 soft india-rubber ball B and is attached to the same. Immediately behind the flange of the tube S, which serves as an abutment to the rubber ball or other elastic receptacle, the tube has a small perforation, through which 45 the liquid sucked into the ball may enter the comb-shaped extremity of the tube and the distributing-tubes Z. Between the rubber ball and the comb-shaped extremity can be inserted a small two-way cock H, Fig. 3. The 50 thin end of the plug of this cock is rounded and connected with a small india-rubber suction-pipe, through which the liquid necessary

to the treatment of the scalp may be drawn directly from the bottle, so as to avoid waste; but the cock H is not absolutely necessary in 55 using this apparatus. The cock H is, if provided, placed so as to prevent liquid from flowing to the outlet-tubes Z, while the passage through the thin end of the plug is open and communicates through the india-rubber 60 pipe with the liquid-reservoir. Liquid is now drawn in through the said plug or tubes by inflating the india-rubber ball B, which previously had been compressed, thereby filling 65 the ball. When the latter has again assumed 70 its normal shape, the cock H is turned ninety degrees, thereby closing the passage through the end of the plug and opening the inlet to the tubular teeth or tines of the comb-shaped extremity. Subsequently the tines are passed 75 between the hairs onto the place of the scalp which is to be treated, a portion of the liquid is pressed out of the tines, and the operation is repeated at other places of the scalp until the entire scalp has been uniformly moistened, while the hairs remain dry.

Having now particularly described and ascertained the nature of the said invention and in what manner the same is to be performed, I declare that what I claim is—

An apparatus of the character described comprising a comb-shaped member having hollow teeth, said member having also a screw-threaded opening formed in its upper side, said opening communicating with the 85 hollow teeth; a hollow tube, having its upper end closed, the lower end being screw-threaded to fit within said screw-threaded opening, said tube having a radial and relatively small perforation, and also having an annular 90 flange; and a compressible and distensible ball or bulb having a single opening removably secured between the top of said comb-shaped member and said flange, said bulb entirely inclosing said tube, substantially as 95 described.

In testimony that I claim the foregoing as my invention I have signed my name, in presence of two subscribing witnesses, this 13th day of August, 1900.

FRANZ MOSTERTS.
